UNITED STATES PATENT OFFICE

LOUIS A. SUEKOFF, OF CHICAGO, ILLINOIS

MATTRESS AND METHOD OF MAKING SAME

Application filed May 6, 1929. Serial No. 360,925.

This invention relates to the mattress making art and has for its object to provide a novel method of finishing mattresses of a certain type to produce a very attractive and durable structure while eliminating expensive hand labor which is now incident to the production of so-called roll-edges along the corners of such structures.

My present invention relates in part particularly to that type of springfilled mattress shown and described in Letters Patent of the United States No. 1,700,339, dated January 29, 1929, and more directly to the specific form of that structure shown and described 15 in my pending application for United States Letters Patent, Serial No. 317,816, filed November 7, 1928, wherein top and bottom padded walls, including means for engaging the same with rows of interposed springs, 20 are first made up, then associated with the springs to provide a structure open at sides and ends.

This structure presents the problem of providing a cheap and efficient means of or 25 method for attaching the boxing strip to close the open sides and ends and, at the same time, produce an attractively finished structure which shall present roll-edges. The mere attachment of an ordinary boxing strip 30 is, of course, easy of accomplishment but it was found difficult to form an attractive up-standing roll-edge on or to otherwise so form the peripheral corners as to give the structure a very attractive appearance and also render 35 it very strong and durable without greatly adding to the expense of production.

The main object of the present invention is to provide a method whereby the attachment 40 of the boxing and formation of the roll-edges is accomplished by a single operation capable of being carried out by a sewing machine.

In order that the method of the present invention may be readily understood, reference is had to the accompanying drawings 45 wherein:

Fig. 1 is a fragmentary perspective view of a mattress finished by the method of this invention.

Fig. 2 is a fragmentary perspective view of a suitable type of padded boxing strip used. 50

Fig. 3 is a fragmentary vertical section of a mattress of the type above referred to adapted for finishing by the method of the present invention.

Fig. 4 is a sectional view similar to Figs. 55 3 and 5 showing the finished structure.

Fig. 5 is a detail fragmentary vertical section showing a free edge portion of a top wall of the structure of Fig. 3 and a portion 60 of the boxing strip of Fig. 2 disposed in relative position and condition for association by a line of stitching.

Fig. 6 is a fragmentary perspective view of a mattress casing made in accordance with this invention and presenting an open end 65 for the reception of a filler and illustrating a modification of the structure of Figs. 1 to 5.

Fig. 7 is a fragmentary perspective section view of a top or bottom wall of the casing of Fig. 6. 70

Fig. 8 is a view similar to Fig. 7 showing a peripheral edge portion of a top or bottom wall and a boxing strip secured together.

Fig. 9 is a view similar to Fig. 5 showing 75 a corner portion of the completed casing in section.

While the invention has special reference to the particular type of mattress structure above referred to and illustrated in the accompanying drawings, I desire it to be understood that it may be applied to other types of mattresses without departing from the invention as defined in the appended claims. 80

The mattress structure shown in Fig. 3 comprises top and bottom walls 1 and 2, each 85 of which comprises two layers 3 and 4 of burlap or other suitable fabric on one of which lines are suitably printed or otherwise applied which divide its surface into small square areas. In each of the latter, on the 90

layer or sheet 4, there is provided a central opening or a diagonal slot of less length than the diagonal of the area, these markings and slots being omitted from illustration.

5 The two layers 3 and 4 are then joined by lines of stitching extending longitudinally and transversely of said layers or sheets and following alternate lines impressed or imprinted on the layer or sheet 4 so that said 10 lines of stitching define areas each containing four of the small square areas except along the edges and corners.

Padding, such as cotton, is then laid upon the layer or sheet 3, a cover fabric 5, such as 15 ticking, laid upon the padding and said ticking and padding then secured to the two layers 3 and 4 by means of lines of stitching 6 and 7, which alternate with the first mentioned lines of stitching so that now all of the 20 square areas of the layer 4 are bordered or defined by lines of stitching, the padding and ticking forming "biscuits", each of an area of four of the small square areas. The several fabrics 3, 4 and 5 and the layer of 25 padding are of such width and length as to provide free peripheral edge portions 8.

The several lines of stitching above mentioned serve, conjointly with the fabrics 3 and 4, to provide square flat pockets which 30 receive the end coils of the springs 9.

The above described structure and the method of making the same are fully illustrated and described in the above mentioned pending application but may be regarded as 35 unimportant and not limiting the present invention to improvements in and upon that particular type of structure as the only requisite of that or any other structure to which the present invention is applied is that it shall 40 present free edge portion 8 peripherally of the top and bottom fabrics of a mattress structure which may be spring-filled or may be filled with padding materials of any kind commonly used for mattress stuffing.

45 While in the instance illustrated, the free edge portions 8 include several fabrics and interposed padding, which is preferable, I desire it to be understood that this is not essential to the present invention as will hereinafter appear.

Upon completion of the mattress top and bottom walls of the casing and the association of the springs 9 therewith, the boxing strip is applied in the following manner.

55 A padded boxing strip 10 is used. This, in the instance illustrated, consists of two strips 11 and 12 of suitable fabric between which is a layer of padding such as cotton, the strips 11 and 12 being joined by stitch-chains 13 extending transversely of the longitudinal edges of the said strips and through the padding. These stitch-chains 13 may be spaced from each other as desired and may be arranged in any other manner than that 60 shown as their sole function for the purposes

of this invention is to produce a padded or quilted boxing having an appreciable average thickness. The degree of that thickness may be defined as being required to be sufficient, upon folding an edge portion of the 70 quilted boxing upon the body thereof as shown in Fig. 4, to produce sufficient bulk to form a roll edge of ample cross-sectional dimensions to produce a rounded or corner finish proportionate to the dimensions of the 75 mattress body to render the whole mattress attractive.

The mattress body and quilted boxing strip 10 having been respectively produced, the next steps, which constitute the essence of 80 this invention, consist in folding the free edge portions 8 of the top and bottom walls of the mattress body upon themselves as shown in Fig. 4, then folding the longitudinal edge portions of the boxing strip 10 upon the 85 inner face of the body thereof as shown in Fig. 4, then positioning the folded edge portion 8 and folded boxing strip 10 in the relation shown in Fig. 4, and then passing a stitch-chain 14 through these respective folded elements to thus, in a single operation, attach one folded side edge portion of the boxing strip 10 to the top or bottom wall of the mattress body and thus form the roll-edge without resort to the further operation of inserting roll-edge ties such as have been heretofore necessary.

Incidentally this operation also forms a 90 very attractive bead or piping 15 which lies just inwardly of the roll-edge of the boxing and renders the whole structure very attractive in appearance. This piping may include 95 some of the padding of the edge portions 8 or may be limited to a fold of the ticking only as the mattress maker may elect.

100 It will be appreciated, of course, that the folding of the edge portion 8 and of the edge portions of the boxing is done progressively around the mattress body immediately in advance of the stitching 14 which may, of course, 105 be effected by hand though machine sewing is preferable because of greater speed, lower cost and neater appearance.

Obviously the folded edge portions joined by the stitch-chain 14 may be basted in advance of the stitching, if desired, though this 110 has been found unnecessary in practice.

The invention is particularly advantageous in that it greatly reduces and practically eliminates the cost of the hand labor incident 115 to the present method of forming such a roll-edge and produces a far stronger and more durable finished structure, it being common practice to grasp the roll-edges of mattresses 120 in handling the same and causing the ordinary roll-edge ties to break. The stitch-chain 14 is far stronger than the ordinary roll-edge ties and permits of this practice 125 without danger to the mattress.

I am aware that it has been proposed in the 130

past to produce a quilted boxing having roll-edges completed prior to attaching said boxing to the mattress body but that method has not to my knowledge been used commercially as not constituting a practical solution of the problem of obviating the hand labor incident to the formation of roll-edges on mattresses.

While the invention is particularly intended and adapted for the class of mattresses first 10 above referred to wherein the springs are so associated with the top and bottom walls of the structure as to be held in proper relative positions thereby, the invention is also very well adapted for the production of mattress casings adapted to receive completed spring 15 assemblies or any other type of mattress filler.

Such a casing is shown in fragmentary perspective view in Fig. 6 as consisting of top and 20 bottom walls 16 and 17 each comprising an inner ply 18 of suitable fabric, an outer ply 19 of ticking and interposed padding, said fabrics 18 and 19 being joined by lines of stitching 20 which, in the instance illustrated, 25 are parallel with each other and extend transversely of the side edges of said walls 16 and 17.

The boxing strip 21 is identical, preferably, 30 with that shown in Fig. 2, but may be of any other form of quilted structure. This strip 21 is folded exactly as is the strip 10 of the structure of Figs. 1 to 5 inclusive and is preferably laid upon the bed plate of a sewing machine with its folded edge portion uppermost. A peripheral free edge portion 22 of a 35 top or bottom wall is then placed in folded position as shown in Fig. 8 to overlie the folded edge portion of the boxing strip and the stitch-chain 23 then passed through 40 the several folded elements to thus join the same and at the same time form the roll-edge 24 and the piping 25 of the mattress casing as shown in Figs. 6 and 9.

After the boxing strip has thus been secured to the sides and one end of the top and bottom walls, leaving the portion 26 of 45 said strip free, as shown in Fig. 6, a spring assembly or other filler is inserted into the casing and the portion 26 of the boxing strip is then secured in the manner described with 50 reference to the structure of Figs. 1 to 5, inclusive.

The structure resulting from the above described method as regards that shown in Figs. 55 1 to 5 and Figs. 6 to 9, constitutes an improved article of manufacture for reasons hereinabove set forth and is defined in some of the appended claims.

I claim as my invention:

60 1. The method of finishing mattresses which consists in first completing quilted top and bottom walls of the casing, then applying and securing to the peripheral edge portions of said walls the folded edges of a quilted boxing strip and passing stitch-

chains through said edge portions of said walls and the folded edge portions of the boxing strip to thereby secure the latter to said walls to complete the casing and at the same time form permanent roll-edges on said 75 casing.

2. The method of finishing mattresses which consists in first completing quilted top and bottom walls of the casing, then folding upon themselves the peripheral free edge 75 portions of said top and bottom walls successively, then applying and securing to the peripheral edge portions of said walls the folded edges of a quilted boxing strip and passing stitch-chains through said edge portions of said walls and the folded edge portions of the boxing strip to thereby secure the latter to said walls to complete the casing and at the same time form permanent roll-edges on said casing and piping bordering 85 said roll-edges.

3. The method of making mattress casings which consists in first producing quilted top and bottom wall members, each having a peripheral free edge portion, and producing a quilted boxing strip of appreciably greater 90 width than the depth of the casing to be produced, then folding the top and bottom edge portions of the boxing strip inwardly to overlap the body thereof, then passing stitch-chains through the folded edge portions and body of the boxing strip to extend through the free edge portions of the top and bottom walls to thereby secure the boxing strip to said walls and at the same time form roll-edges on the boxing strip and complete the 95 casing.

4. The method of making mattress casings which consists in first producing quilted top and bottom wall members, each having a 100 peripheral free edge portion, and producing a quilted boxing strip of appreciably greater width than the depth of the casing to be produced, then folding the top and bottom edge portions of the boxing strip inwardly to overlap the body thereof, and folding the free edge portions of walls upon themselves inwardly and then passing a single stitch-chain 105 successively through said folded edge portions of each of said walls and the folded edge 110 portions of said boxing strip to thereby secure the latter to said walls to complete the casing and at the same time form roll-edges on said boxing strip and piping on said walls 115 bordering said roll-edges.

5. A mattress casing comprising quilted top and bottom walls, a quilted boxing strip having its top and bottom edge portions folded over inwardly to overlap the inner face of 120 said strip, and a pair of parallel stitch-chains extending through the body and folded over edge portion of the boxing strip and through the peripheral edge portions of the top and bottom walls thereby completing the casing 125 130

and providing permanent roll-edges on the boxing strip.

6. In a mattress casing, a top or bottom wall having a free peripheral edge portion, a quilted boxing strip having a longitudinal edge portion folded over inwardly to contact with and partially overlap the intermediate portion of said strip, and a single stitch-chain extending through the folded edge portion of said boxing strip and the peripheral edge portion of the wall.

LOUIS A. SUEKOFF.
